TOILET SUPPORT UNIT FOR INVALIDS

Robert A. Wood, 5901 Ravenswood, Chicago, Ill.

Filed Feb. 5, 1962, Ser. No. 68,667

Term of patent 14 years

(Cl. D4—5)

Fig. 1

Fig. 2

FIG. 1 is a perspective of the toilet support unit for invalids, in accordance with this invention; and

FIG. 2 is a fragmentary front perspective of the left grip as shown in FIG. 1.

The side not shown in FIG. 1 is substantially like the side shown, and the broken lines shown in FIG. 1 are for illustrative purposes only. The sides and front of the hand grips are scalloped at their lower edges.

I claim:

The ornamental design for a toilet support unit for invalids, as shown and described.
